US0D1039603S

(12) **United States Design Patent** (10) **Patent No.:** **US D1,039,603 S**
(45) **Date of Patent:** **** Aug. 20, 2024**

(54) **LEARNING MACHINE**

(71) Applicant: **BEIJING XINTANG SICHUANG EDUCATION TECHNOLOGY CO., LTD**, Beijing (CN)

(72) Inventors: **Tingting Xue**, Beijing (CN); **Boxun Jing**, Beijing (CN); **Duo Zheng**, Beijing (CN); **Lixue Yang**, Beijing (CN)

(73) Assignee: **BEIJING XINTANG SICHUANG EDUCATION TECHNOLOGY CO., LTD (CN)**

(**) Term: **15 Years**

(21) Appl. No.: **35/518,880**

(22) Filed: **Jul. 24, 2023**

(80) **Hague Agreement Data**

Int. Filing Date: **Jul. 24, 2023**

Int. Reg. No.: **DM/232571**

Int. Reg. Date: **Jul. 24, 2023**

Int. Reg. Pub. Date: **Nov. 3, 2023**

(30) **Foreign Application Priority Data**

Mar. 27, 2023 (CN) 202330153748.5

(57) **CLAIM**

The ornamental design for a learning machine, as shown and described.

DESCRIPTION

The patent or application file contains at least one drawing executed in color. Copies of this patent or patent application publication with color drawing(s) will be provided by the Office upon request and payment of the necessary fee.

1. Learning machine
  2. Learning machine
  3. Learning machine
  4. Learning machine
- 1.1 : Front
1.2 : Back
1.3 : Left
1.4 : Right
1.5 : Top
1.6 : Bottom
1.7 : Perspective
1.8 : Perspective
- 2.1 : Front
2.2 : Back

(Continued)

2.3 : Left
2.4 : Right
2.5 : Top
2.6 : Bottom
2.7 : Perspective
3.1 : Front
3.2 : Back
3.3 : Left
3.4 : Right
3.5 : Top
3.6 : Bottom
3.7 : Perspective
3.8 : Perspective

4.1 : Front
4.2 : Back
4.3 : Left
4.4 : Right
4.5 : Top
4.6 : Bottom
4.7 : Perspective
1.1 to **1.8** show a first embodiment of a design of a learning machine; **2.1** to **2.7** show a second embodiment of a design of the learning machine; **3.1** to **3.8** show a third embodiment of a design of the learning machine; and **4.1** to **4.7** show a fourth embodiment of a design of the learning machine.

**1 Claim, 30 Drawing Sheets
(16 of 30 Drawing Sheet(s) Filed in Color)**
